UNITED STATES PATENT OFFICE.

N. A. PATTERSON AND WILLIAM L. RAMSEY, OF KINGSTON, TENNESSEE.

WASHING-MACHINE.

Specification of Letters Patent No. 29,714, dated August 21, 1860.

To all whom it may concern:

Be it known that we, N. A. PATTERSON and W. L. RAMSEY, both of Kingston, in the county of Roane and State of Tennessee, 5 have invented a new and Improved Clothes-Washing Machine; and we do hereby declare that the following is a full, clear, and exact description of the same, reference being had to the annexed drawings, making 10 a part of this specification, in which—

Figures 1, and 2, are side sectional views of our invention, the two planes of section crossing each other at right angles.

Similar letters of reference indicate corresponding parts in both figures.

This invention consists in the employment or use of a circular perforated pressure plate placed within a suitable tub and operated as hereinafter shown, whereby clothes may be 20 perfectly cleansed in an expeditious manner, and without the least injury to the same, the wear produced by friction in the various rubbing machines hitherto devised for washing clothes being entirely obviated.

25 To enable those skilled in the art to fully understand and construct our invention we will proceed to describe it.

A, represents a tub which may be of the usual form, and B, is a frame composed of 30 two uprights *a*, *a*, connected at their upper ends by a cross piece *b*, the uprights *a*, *a*, being attached to a suitable base or platform *c*, on which the tub A, is placed, the tub being between the two uprights.

35 C, is a cross bar the ends of which are attached to slides *d*, *d*, that are fitted in grooves *e*, at the inner sides of the uprights *a*, *a*, the slides being allowed to work freely up and down in the grooves *e*, *e*. Through the 40 center of the bar C, a vertical shaft D, passes, the lower end of which has a crank *f*, attached with a vertical pendant *g*, at its outer end. The lower end of this pendant is hol-

lowed out so as to form a socket *h*, to receive a ball *i*, at the upper end of a shaft *j*, 45 on which a circular perforated and dish shaped pressure plate E, is placed said plate fitting within the tub A, as shown clearly in both figures. The lower end of the shaft *j*, is stepped at the center of the bottom of the 50 tub A, as shown at *k*, the step *k*, being coincident or in line with the shaft D, of crank *f*.

The operation is as follows. The tube A, is supplied with a requisite quantity of suds 55 or soap and water and the clothes to be operated upon are placed in the tub beneath the plate E. The crank *f*, is then rotated by any convenient power and the clothes beneath the plate E, are subjected to a pressure by said plate which has what may be termed a wabbling motion and causes the suds to be forced through the texture of the clothes thoroughly cleansing the same in a very short time without injury and without 65 breaking buttons which may be attached to them.

The plate E, may be readily adjusted in the tub A, and removed therefrom so that the clothes may be placed in and removed 70 from the tub by adjusting the bar C, and consequently the crank *f*, in which the upper end of the shaft *j*, is fitted.

Having thus described our invention what we claim as new and desire to secure by 75 Letters Patent, is:

The circular perforated and dish-shaped pressure plate E, placed within a tub A, and having the upper end of its shaft *j*, fitted in a crank *f*, of a shaft D, all being arranged 80 as and for the purpose set forth.

N. A. PATTERSON.
WM. L. RAMSEY.
